Inventor:

Z. Breed
per Daniel Breed Atty.

United States Patent Office.

Z. BREED, OF WEARE, NEW HAMPSHIRE.

Letters Patent No. 91,709, dated June 22, 1869.

IMPROVED FIRE-EXTINGUISHER.

The Schedule referred to in these Letters Patent and making part of the same.

To all whom it may concern:

Be it known that I, Z. BREED, of Weare, in the county of Hillsborough, and State of New Hampshire, have invented a new and useful Improvement in Fire-Extinguishers; and I do hereby declare that the following is a full and exact description thereof, reference being had to the accompanying drawings, and to the letters of reference marked thereon.

My invention consists—

First, in so constructing and arranging a fire-extinguisher, charged with water and chemicals, that the charge may be ignited, or the chemicals set in chemical action, after the can or vessel has been closed.

Second, in the arrangement for igniting the charge or a fuze or fulminate connected therewith, by means of a dart, wire, or other equivalent means, passing through and worked from the outside of the can.

Third, in holding the charge above the water, and in a position to be dropped into the basket, or upon the support for the charge, while undergoing the combustion or chemical decomposition.

In the accompanying drawings—

Figure 1 is a vertical section of the cap of a fire-extinguisher, with my improved devices attached.

Figure 2 is a bottom view of the same.

On the bottom of the cap B is placed a charge-holder, A, of suitable size and form, to receive the end of the package containing the charge, and hold the same until it is desired to ignite the package.

A dart, D, passes through the top of the cap, as seen in fig. 2, and is provided with a point, d, for pene-

trating the paper, and igniting the fulminate by friction. This dart is held in place by a coiled spring, C.

By a gentle pressure or stroke upon the knob or top of the dart, the latter is thrust down in contact with the charge, rupturing the package, igniting the charge or fulminate, and also dropping or pushing off the charge.

If desired, this dart may be packed, to make the joint with the cap more secure. The cap itself has a rubber packing, E.

I do not limit myself to the precise arrangement, as a wire may be pulled, or any other device may be employed for producing either friction or percussion.

Having thus fully described my invention,

I claim—

1. Igniting the charge in a fire-extinguisher after the can or vessel has been closed, substantially as set forth.

2. The dart D, or its equivalent, operated from the outside, yet acting upon the inside of the fire-extinguisher, for igniting the charge or fulminate, substantially as described.

3. Supporting or holding the charge by means of the charge-holder A, or its equivalent, and dropping the same after the can or vessel is closed, substantially as set forth.

Z. BREED.
